UNITED STATES PATENT OFFICE.

JOHN SAPRONES, OF BRIDGEPORT, CONNECTICUT.

PULP-WOOD PEELER.

Application filed June 5, 1924. Serial No. 718,053.

To all whom it may concern:

Be it known that I, JOHN SAPRONES, a citizen of Greece, residing at Bridgeport, in the county of Fairfield and State of Connecticut, have invented certain new and useful Improvements in Pulp-Wood Peelers, of which the following is a specification.

This invention relates to new and useful improvements in pulp wood peelers.

10 An important object of the invention is to provide apparatus which is capable of peeling off the bark from pulp wood or other kinds of logs.

A further object of the invention is to 15 provide a peeler which will cut uniform strips from logs irrespective of the diameter of the same.

A still further object of the invention is to provide means for mechanically feeding 20 logs through the peeling portion of the apparatus and for centering the logs while traveling through such peeling portion.

Other objects and advantages of the invention will be apparent during the course 25 of the following description.

In the accompanying drawing forming a part of this specification and in which like numerals are employed for designating like parts throughout the same,

30 Figure 1 is an elevational view of the entire apparatus embodying this invention and illustrates a pair of logs being treated therein,

Figure 2 is a top plan view of the apparatus illustrated in Fig. 1,

Figure 3 is a detail elevational view of one set of peeling elements with the remaining sets of peeling elements illustrated in dotted lines to properly disclose the relative arrangement of all of said elements,

Figure 4 is a detail perspective view of one cutting element with its tensioning spring and guide,

Figure 5 is a detail elevational view of the 5 cutting elements illustrated in Fig. 1 and shows in longitudinal section a log being operated upon by said cutting element, and

Figure 6 is a fragmentary elevational view of the feeding conveyor employed for moving logs through the peeling portion of the apparatus.

In the drawing, wherein for the purpose of illustration is shown a preferred embodiment of this invention, the numeral 5 designates 55 the side bars of a base frame which is em-

ployed for supporting the apparatus and is retained in an elevated position in respect to the ground by the legs 6. A desirable number of cross braces 7 are provided for keeping these side bars 5 in fixed relation 60 with respect to each other and for strengthening the base frame.

Carried by the receiving end of the base frame is a trough 8 which is of substantially V-shape and is formed of the perpendicular 65 extending braces 9 to which are secured the longitudinally extending boards 10. The discharge end of the base frame is also provided with a substantially V-shaped trough which is formed of the braces 11 and boards 70 12.

Suitably supported adjacent the receiving end of the base frame is a transversely extending horizontal shaft 13 which carries a roller 14. Suitably journaled upon the base 75 frame in proximity to the outer ends of the boards 10 is a transverse shaft 15 carrying a roller 16. Mounted upon these rollers 14 and 16 is an endless belt 17, best illustrated in Fig. 6. This belt 17 is provided with a 80 plurality of transversely extending, pivotally mounted bars 18 having sharpened edges 18^a. Suitably keyed to the shaft 15 is a pulley wheel 19 which carries the belt 20 that rides upon the pulley wheel 21 carried 85 by the power shaft 22 which is journaled in the bearing 23 carried by the base frame. It is to be understood that suitable power is provided for driving this shaft 22 for the purpose of causing the belt 17 with its 90 bars 18 to travel in the direction of the arrow in Fig. 6. This belt 17, with its bars 18, is intended to feed logs L through the apparatus. It is to be understood that these bars 18 are pivotally secured to the belt 17 95 in such a manner that they will pivot forwardly in the direction of travel of the belt and that they are prevented, by any suitable means, from pivoting rearwardly in the opposite direction of the travel of the belt. As 100 a log L is started onto this belt 17, the bars 18 positioned between the ends of the log will pivot forwardly for causing their sharpened edges 18^a to engage the outer surface of the belt, the bars not being able to support the weight of a log. These bars will be pivoted forwardly until the rear end of the log passes onto the belt whereupon the next bar 18 passing around the roller 14 105 will be placed in engagement with the rear 110

end of this log and will be retained in a vertically extending position for feeding the log longitudinally forwardly.

- Carried by the boards 10 are a circular series of reversely curved spring arms 24 which are employed for centering the logs L in respect to the cutting elements, to be described at a later point. The transversely extending brace bar 7 positioned adjacent the rear ends of the boards 12, is provided with a perpendicularly extending ring 25 which cooperates with the said brace bar 7 for carrying a circular series of spring arms 26 which are adapted for engaging the front end of the logs as they are fed out of the central portion of the apparatus onto the endless conveyor belt 27 which is carried by rollers 28 and 29 mounted on shafts 30 and 31. The shaft 30 is provided with a pulley 32 upon which rides a belt 33 which engages a second pulley 34 carried by the shaft 15. It will, therefore, be seen that the conveyor belt 27 travels in unison with the conveyor belt 17.
- Suitably secured to the side bars 5 of the base frame, as by the V-shaped braces 35, are a series of rings 36, 37, 38 and 39 which are concentrically arranged with the arms 24 and 26. Extending between the rings 36 and 37 and suitably secured thereto are a desired number of longitudinally extending bars 40 which are equi-spaced around the peripheries of the said rings. Extending between the rings 37 and 38 are the equi-spaced longitudinally extending bars 41 which are positioned laterally of the bars 40 or staggered in respect thereto. Extending between the rings 38 and 39 are a third set of longitudinally extending bars 42 which are positioned laterally of the bars 41 in such a manner that they will be arranged in staggered relation with these bars and also the bars 40. By inspecting Figs. 1, 2 and 3, it will be seen that the rings 36, 37 and 38 are provided with a plurality of pivoted arms 43 which are connected to these rings in longitudinal alinement with the bars 40, 41 and 42 for the purpose of arranging these arms 43 in staggered relation in respect to each other as best illustrated in Fig. 3. For the purpose of retaining the outer ends of these arms in proximity to a log L passing through the rings 36 to 39 inclusive, the arms 43 are each provided with a rod 44 which extends through a suitable opening in one of the bars 40, 41 or 42 and has a spring 45 encircling the same and positioned between its arm 43 and the respective bar 40, 41 or 42.
- In Figs. 4 and 5, an arm 43 is illustrated in detail as having removably attached to its outer end a transversely extending cutting blade 46 of arcuate shape which is positioned with its cutting edge 47 presented to the logs L in such a manner that as they are

fed longitudinally through the apparatus toward the discharge end of the base frame, the bark B will be peeled off, as best illustrated in Fig. 5, into longitudinally extending strips which will be of equal length to the length of the log being peeled. The arm 43, in Figs. 4 and 5, is also illustrated as being provided with an arcuate guiding blade 48 which is pivotally secured, as at 49, and is clamped in its adjusted position by the bolt 50 received within an arcuate slot in the said blade 48.

It is believed that the manner of feeding logs through the peeling portion of this apparatus has been sufficiently described heretofore and for this reason the action of the cutting elements 46 will be described at this point. It is intended that only the arms 43 pivotally carried by the rings 37 and 38 be provided with the guiding blades 48. As a log is passed through the ring 36, and as it approaches the ring 37, the cutting elements 46 carried by the arms 43 pivotally mounted upon this ring 36 will start peeling strips from the said log. As the front of the log approaches the arms 43 carried by the ring 37, the guiding blades 38 will align with one edge of the bark still remaining upon the log and these blades will guide the cutting elements 46 carried by the arms 43 pivotally secured to the ring 37 so that a second strip will be cut from the log to the left of each of the first strips. The log will then be fed through the rings 38 and 39 and the cutting elements 46 carried by the arms secured to the ring 38 will cut the remaining strips of bark from the log, the blades 48 carried by these last mentioned arms 43 being employed for guiding the cutting elements 46.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:—

1. In a device of the type described, a base frame, an endless conveyor belt at the receiving end of the base frame, transversely extending bars pivotally carried by said belt for engaging logs to feed them in the direction of movement of said belt, an endless conveyor at the discharge end of the frame for feeding logs off of the latter, a group of resiliently mounted bark peeling blades carried by the base frame between said endless conveyors, a circular series of reversely curved resilient arms carried by said frame at one end of the group of peeling elements and a circular series of inwardly curved resilient arms carried by said frame

- at the other end of the group of peeling elements for centering the logs while being operated upon by said elements, and means for driving the endless conveyors in unison.
- 5 2. In a device of the type described, a base frame, a framework carried by said base frame, a plurality of sets of arms pivotally carried by said framework, the arms in each set being arranged in circular series 10 and positioned in staggered relation to the arms of the other sets, means for yieldably retaining the free ends of said arms in close proximity to the axes of their respective circles, bark peeling blades extending laterally from the free ends of said arms, and means for feeding logs axially through the circular series of peeling means.
- 15 3. In a device of the type described, a base frame, a plurality of concentrically arranged rings carried by said base frame, a plurality of arms pivotally carried by said rings, means for yieldably retaining the free ends of said arms in close proximity to the axes of said rings, a bark peeling blade extending laterally of the free end of each arm, means for feeding logs through said rings, and a circular series of reversely curved spring arms for centering said logs while being fed through said rings.
- 20 4. In a device of the type described, a base frame, an endless conveyor carried by the receiving end of said frame, an endless conveyor carried by the discharge end of said frame, said conveyors being adapted for feeding logs longitudinally, a plurality of rings carried by said frame between said conveyors, a plurality of arms carried by each ring, resilient means for forcing the free ends of said arms toward the axes of 25 said rings, a bark peeling element carried by the free end of each arm, the bark peeling elements associated with each ring being arranged in staggered relation to the bark peeling elements carried by the remaining rings, means for centering the logs passing through said rings, and means for driving said endless conveyors in unison. 45
5. In a device of the type described, a base frame, an endless conveyor belt carried by the receiving end of said frame, an endless conveyor belt carried by the discharge end of said frame, said conveyors being adapted for feeding logs longitudinally along said frame, a plurality of equi-spaced rings carried by said frame between said conveyors, a plurality of pivotal arms carried by each ring, resilient means for forcing the free ends of said arms toward the axes of said ring and with the arms extending toward the discharge end of the frame, a laterally projecting bark peeling blade carried by the free end of each arm, the bark peeling blades associated with each ring being arranged in staggered relation to the bark peeling blades carried by the remaining rings, a circular series of reversely curved spring arms arranged at one end of the plurality of rings and extending toward the discharge end of the frame and a circular series of inwardly curved spring arms arranged at the other end of the plurality of rings and extending toward the discharge end of the frame, whereby said logs will be centered in respect to the bark peeling elements while passing thru the rings, and means for driving said endless conveyors in unison. 55 60 65 70 75

In testimony whereof I affix my signature.

JOHN SAPRONES.
